(57) **CLAIM**

The ornamental design for the case for mobile phone, as shown and described.

DESCRIPTION

FIG. 1 is a perspective view of the case for mobile phone showing our design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective, open view thereof showing receipt of a mobile phone.

The broken line showing of environment in the drawing of FIG. 8 is for illustrative purposes only and forms no part of the claimed design.
